UNITED STATES PATENT OFFICE.

THOMAS E. COX, OF BIRMINGHAM, ALABAMA, ASSIGNOR, BY DIRECT AND MESNE ASSIGNMENTS, OF ONE-FOURTH TO WILLIAM C. MUCKLEROY, ONE-FIFTH TO CHARLES M. WALL, ONE-SIXTH TO BENJAMIN P. WILLIAMS, AND TWO-FIFTEENTHS TO WILLIAM R. STAFFORD, ALL OF TAMPA, FLORIDA.

CAR-COUPING.

1,156,029.

Specification of Letters Patent.

Patented Oct. 5, 1915.

Application filed April 28, 1915. Serial No. 24,590.

To all whom it may concern:

Be it known that I, THOMAS E. Cox, a citizen of the United States of America, residing at Birmingham, in the county of 5 Jefferson and State of Alabama, have invented certain new and useful Improvements in Car-Couplings, of which the following is a specification.

My invention relates to an improvement 10 in car couplers of the Janney type having a swinging knuckle pivotally connected to the draw-head and provided with a tail-wing adapted to swing within a recess in the draw-head and to be there engaged by a 15 suitable locking mechanism, such, for instance, as that described and claimed in Letters Patent No. 1,123,694, issued to me on the 5th day of January, 1915. In practice 20 coupler heads of this type most frequently break across one or the other of the lugs to which the knuckle is pivoted as the maximum jar or strain comes across the part of the lug where it is weakened by the opening for the pivot pin. When either 25 one of the lugs is thus injured or broken it necessitates the discarding of the entire coupler head and lays up the car for a considerable time for effecting the repairs.

The object of my invention is to reduce 30 to a minimum the maintenance expense of coupler heads by providing the head with sockets in which knuckle holding blocks are detachably mounted and I pivot the knuckle between perforated lugs on these blocks instead of to lugs integral with the draw-head. It therefore follows that any breakage 35 across either of the lugs will involve only the replacement of its respective block without disturbing the draw-head. This arrangement also permits of the use of metal 40 of high tensile strength in the blocks and lugs to make them capable of withstanding greater strains than when made of the same grade of steel as the draw-head.

My invention further consists in the novel 45 manner in which these blocks are formed and in the interlock by which they are made rigidly fast in the draw-head, it being obvious that it is difficult to devise a means to 50 perfectly accomplish this end because of the great strains or jars to which couplers are subjected.

My invention further comprises the novel

details of construction and arrangements of parts which are hereinafter described and 55 claimed, and which in their preferred embodiment only are illustrated in the accompanying drawings, in which:

Figure 1 is a plan view of the draw-head with the knuckle pivoted between lugs on 60 the detachable blocks. Fig. 2 is a front elevation of the draw-head showing the knuckle removed. Figs. 3 and 4 are detail plan and outer side elevation views of the lower knuckle block. Fig. 5 is a vertical sectional 65 view taken on the plane $x-x$ of Fig. 2, and showing the blocks in dotted lines and the wedge means for locking them rigidly in position. Fig. 6 is a partial sectional view taken on the line $y-y$ of Fig. 5 showing 70 the lower block in plan view seated and wedged in the draw-head, the wedge lock being omitted.

Similar reference numerals refer to similar parts throughout the drawings.

In the illustrated embodiment of my invention the draw-bar 1 is provided with a coupler head 2 having at one side a jaw 3 and at the other side an offset portion 4 which is recessed to receive a tail-wing 5 of 80 the knuckle 6 and also the removable blocks 7 and 8 which carry the lugs 9 between which the knuckle is pivoted by a removable pin 10.

The draw-head 1 and the offset portion 4 85 are provided with a common recess or chamber 11 which receives the tail-wing and also the vertically movable locking pin 12, the construction and operation of which are more fully described in my Letters Patent 90 No. 1,123,694, and which will drop in front of the tail-wing and lock the knuckle in its closed position.

The principal feature of my present invention relates to the construction of the 95 knuckle blocks 7 and 8 and the manner of detachably mounting them in the head so that they will stand all compression and draft strains on the knuckle to the same extent and with the same strength as if they 100 were integral parts of the draw-head but which will have the advantage of being replaceable when broken without requiring the replacement of the draw-head. The blocks 7 and 8 are similar in design and construction except that the interlocking portions

thereof are reversed for respective engagement with the upper and lower portions of the draw-head. The block shown in Fig. 3 is an inverted or bottom view of the upper block 7, while the block shown in Fig. 6 in top plan view is the lower block 8. Each block is formed by an oblong steel casting provided at its outer end with the perforated lug 9 and having at the inner end on the top face of the block 7 and on the bottom face of the block 8 an undercut lug 13 having its rear face 14 beveled. To give the lug great strength, its base portion is thickened and it extends from side to side across the lug.

On the opposite inner faces of the blocks 7 and 8 I provide a raised shoulder or enlargement 15 having a curved vertical bearing face extending from the outside inner corner of the lug 9 to the inside corner of the lug where it joins a rounded face conforming to the curvature of the front face of the draw-head with which it stands flush and forming the forward end of an overhanging ledge or shoulder 17 which has the same thickness as the shoulder 15 and extends rearwardly the full length of the shoulder where it joins a forwardly inclined integral lug 18 projecting from the inside edge of each block.

Upon each shoulder 15 is a knuckle bearing shoulder 19 extending on an inward and rearward curve from the outside forward corner of the shoulder 15 to a point near its inside inner corner and having its inner end 20 struck on a convex curve. The inner end 21 of the shoulder 15 terminates a short distance from the inner end of the block and is slightly inclined outwardly and forwardly from its inside to its outside edge. The inner end of each block has its face 22 slightly beveled toward its inside face and away from its lug 13. These inner ends of the blocks when seated in the draw-head 45 are spaced from the rear wall of the draw-head and in order to lock them in position in the head in the manner hereinafter described, I provide for each block a wedge block 23, which blocks have overhanging lugs 24 that lap over the inner ends of the blocks and the wedge blocks are held locked in position behind the blocks 7 and 8 by means of a double wedge 25 which is provided with an opening to receive a retaining bolt 26 so disposed that it is exposed when the knuckle is removed so that it can be engaged by a tool and held so that the nut 27 thereon seated in a countersunk recess 28 in the back of the draw-head can be removed. The draw-head is also provided in its top and bottom walls with holes 29, by means of which the blocks 23 can be pushed in and dislodged from position from behind the knuckle blocks. In order to interlock with the shoulders 13 and 18 of the

knuckle blocks, the coupler is provided with top and bottom enlargements 30 in which are formed inwardly opening undercut notches 31 which correspond in shape to the lugs 13 and the inner side walls 32 are provided with side notches 33 which terminate in reversely disposed notches 34 which correspond in shape with the lugs 18.

In assembling the parts the two blocks are slipped in the coupler head and moved to the dotted position shown in Fig. 5 where their lugs 13 and 18 interlock with the corresponding notches in the head, the wedge blocks 23 are then slipped one at a time between the blocks 7 and 8 and with a tool slid into position behind the block. The lock block 25 is then slipped edgewise between the blocks 7 and 8 and then shifted into position between the inner beveled faces of the wedges 23 and is screwed therein in place by the bolt 26. The knuckle is then mounted between the lugs 9 and the coupler ready for service. To remove a broken block, it is only necessary to take out the bolt 26, work the lock block 25 out, insert a tool through a hole 29 and punch out the wedge block behind the broken knuckle block and then the latter can be shifted rearwardly and downwardly until it clears the notches 31 and 34 in the draw-head and can then be taken out.

What I claim as new and desire to secure by Letters Patent, is:—

1. In a car coupler, a draw-head having at one side a jaw and at the opposite side being provided with a vertical chamber connecting at its center with a tail-wing recess in the draw-head, knuckle blocks detachably mounted in the upper and lower portions of said chamber and having each a perforated lug which projects from the draw-head, interlocking lugs and shoulders on the blocks and draw-head to resist both push and pull thrusts, and removable lock blocks to hold the knuckle blocks in interlocked position in the head.

2. In a car coupler, a draw-head having a vertical recess at one side and a knuckle, of detachable retaining means for the knuckle comprising lugs between which the knuckle is pivoted, a shank integral with each lug and adapted to fit into said vertical recess, a transverse undercut lug on the outside face of each shank, an outwardly and forwardly inclined lug on a side edge of each shank, shoulders in the draw-head to interlock with said lugs, and a plurality of lock blocks which are adapted to hold each other in position and to hold the shanks rigidly interlocked with the draw-head.

3. In a car coupler, a draw-head having at one side a chamber which opens to the front and extends substantially from top to bottom thereof and from front to a point near the rear end of the draw-head, perfo-

rated lugs to which the coupler knuckle is adapted to be pivoted, an elongated block formed integral with each lug and adapted to fit snugly into said chamber, a rear trans-
verse lug on each block, a forwardly in-
clined side lug on each block, recesses in the
side walls of the chamber to permit the side
lugs to be passed in, shoulders in the draw-
head with which lugs on the block interlock,
10 a wedge block adapted to be fitted in behind
each of said lug blocks and the rear wall

of said chamber, and an intermediate lock
block removably mounted between said
wedge blocks to engage and hold them in
position with the lug blocks interlocked 15
with the recesses in the draw-head.

In testimony whereof I affix my signa-
ture in presence of two witnesses.

THOMAS E. COX.
